US00D794183S

(12) **United States Design Patent** (10) **Patent No.:** **US D794,183 S**
Lev et al. (45) **Date of Patent:** **** Aug. 8, 2017**

(54) **DUAL ENDED LIQUID TRANSFER SPIKE**

(71) Applicant: **MEDIMOP Medical Projects Ltd.,**
Ra'anana (IL)

(72) Inventors: **Nimrod Lev**, Savion (IL); **Mordechai**
Bukhman, Netanya (IL)

(73) Assignee: **Medimop Medical Projects Ltd.,**
Ra'anana (IL)

(**) Term: **14 Years**

(21) Appl. No.: **29/502,053**

(22) Filed: **Sep. 11, 2014**

(30) **Foreign Application Priority Data**

Mar. 19, 2014 (IL) 55378

(51) **LOC (10) Cl.** **24-01**

(52) **U.S. Cl.**

USPC **D24/127**

(58) **Field of Classification Search**

USPC D24/127-131, 112-114, 133, 186;

(57) **CLAIM**

The ornamental design for a dual ended liquid transfer spike.

DESCRIPTION

FIG. 1 is a front perspective view of a dual ended liquid transfer spike in accordance with our new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof; and,

FIG. 7 is a bottom plan view thereof.

The broken lines in the figures are to illustrate environmental structure only and form no part of the claimed design.

1 Claim, 6 Drawing Sheets
